UNITED STATES PATENT OFFICE.

JOHN W. ANDERSON, OF GARY, INDIANA.

INDICATING DEVICE FOR COOLING SYSTEMS.

Application filed April 25, 1927. Serial No. 186,547.

My invention relates to indicating devices and particularly to indicating devices of the type shown and described in my copending application, Serial No. 111,345, filed May 24, 5 1926.

Apparatus embodying the present invention also resembles apparatus embodying the invention disclosed in my co-pending applications, Serial Nos. 178,991, 178,992, and 10 178,993, filed March 28, 1927.

Apparatus embodying my invention is particularly adapted to be used in connection with the cooling systems of the internal combustion engine associated with automobiles, 15 or the like, the apparatus being adapted to warn the operator in advance of imminent wastage of the cooling liquid because of overheating and of wastage of the cooling liquid when such wastage is in progress.

20 A particular object of the invention is to provide improved apparatus which will employ the cooling liquid to give a distinctive signal when there is an insufficient supply thereof.

25 Another particular object of the invention is to provide a device of the kind described having improved means for operatively connecting it to an overflow tube of an automobile radiator.

30 Many other objects and advantages of the construction herein shown and described will be obvious to those skilled in the art from the disclosure herein given.

To this end my invention consists in the 35 novel construction, arrangement and combination of parts herein shown and described, and more particularly pointed out in the claims.

In the drawings, wherein like reference 40 characters indicate like or corresponding parts:

Fig. 1 is a central vertical section taken through a device embodying the invention, the device being shown in connection with the 45 filling tube of an automobile radiator;

Fig. 2 is a section taken on line 2—2 of Fig. 1;

Fig. 3 is a fragmentary central section taken through the device shown in Fig. 1, but 50 showing the parts arranged in a different manner;

Fig. 4 is an elevation of a device which embodies another form of the invention, the improved device being shown in connection 55 with the filling tube of an automobile radiator;

Fig. 5 is a section taken on line 5—5 of Fig. 4; and

Fig. 6 is a section taken on line 6—6 of Fig. 4.

Referring for the present to Figs. 1 and 2, I have shown a device embodying a preferred form of the invention, the device being shown mounted upon the filling tube of a radiator which is of the type commonly employed in 60 automobiles, or the like. Only a fragmentary portion of the radiator is shown as the invention does not relate to the construction thereof. The radiator is identified by the reference character 10 and the filling tube is shown at 65 12. In accordance with the usual construction, the radiator 10 is provided with an overflow tube 14 and the upper end of the filling tube 12 is normally closed by a cap 15 which is screw-threaded upon the filling tube. 70

Formed in the cap 15 is a substantially central aperture 22 which is enlarged at its lower end as indicated at 23 to provide a shoulder 24 against which a packing ring 25 seats. Projecting through the aperture 22 is a dome 75 or hollow member 27 which is preferably formed from glass or other transparent material, the member 27 being open at its lower end and being provided with an outwardly extending annular flange 29 arranged to be 80 positioned between the packing ring 25 and a packing ring 30.

Positioned within the dome or glass member 27 is a tubular member 32 which at its lower end is provided with an outwardly extending annular flange 34 which preferably fits snugly in the enlarged portion 23 of the central aperture 22. A washer 35 is preferably inserted between the packing ring 30 and the annular flange 34. Screw-threaded into 90 the cap 15 is a ring 37 which may be manipulated to clamp the annular flange 34, the washer 35, the packing ring 30, the flange 29 and the packing ring 25 in the cap 15, the ring 37 being adapted to cooperate with the 95 shoulder 34 for this purpose.

It will be noted that the lower end of the tubular member 32 flares outwardly to provide the annular flange 34 and that the flared portion is provided with apertures 39 100 through which fluid may pass up into the glass member or dome 37 to be discharged through the tubular member 32 and a tube 40 into the overflow tube 14 which preferably has its lower end in communication with the atmosphere. As shown, the lower end of the tube 40 is preferably flared as at 42 so that it 110

may be easily mounted upon the upper end of the overflow tube 14 and the tube 40 is preferably secured to the overflow tube 14 so that relative displacement therebetween is prevented. Thus, I have shown a projection 44 formed in the tube 40, which projection enters a notch provided in the upper end of the overflow tube 14.

The upper end of the tube 40 is preferably 10 enlarged to provide a bell-shaped portion 47 which is adapted to be positioned in a substantially cylindrical portion 48 of the tubular member 32, the outer diameter of the ball and the inner diameter of the cylindrical portion being substantially equal. The tubular member 32 is preferably constructed intermediate its upper end and the cylindrical portion 48 and is preferably provided with an interior substantially spherical surface 50 which conforms with the outer surface of the ball 47. Above the surface 50, the tubular member is preferably shaped to provide an outwardly extending annular lip 52 which has a function hereinafter described. The tube 40 is preferably provided with an aperture or vent 53 in its wall intermediate its ends to prevent the contents of the cooling system to be siphoned therefrom through the overflow tube 14. If desired, a 20 packing ring 54 may be inserted between the cap 15 and the upper edge of the filling tube 12.

It is readily understood that if the supply of cooling liquid in the cooling system is to 30 be replenished, the cap 15, the glass member 27, the tubular member 32 and the packing ring 37 may be removed as a unit from the filling tube 12. The tube 40 will remain positioned upon the upper end of the overflow tube 14. After the supply of cooling liquid has been replenished, the cap 15 together with the parts carried thereby may be screw-threaded again upon the filling neck or tube 12, the construction being such that 40 the tube 40 will again engage the substantially spherical surface provided in the tubular member 32. Obviously, the ball 47 cooperates with the tubular member 32 to form a ball and socket connection therebetween.

The operation of the above described indicating device is substantially as follows: Assuming that there is a plentiful supply of cooling liquid in the cooling system and that the automobile is in operation, there will be 50 substantially no active indication of any kind in the glass member 27 as long as the temperature of the cooling fluid does not approach its boiling point. However, if for any reason, the temperature of the cooling fluid approaches its boiling point, this fact will be indicated in the glass member 27 by a solid column of water which will rise and fall irregularly and at times disappear from the glass. If the cooling liquid continues to boil 60 a relatively high pressure will be developed

in the radiator and the cooling liquid will flow steadily through the glass member 27 to be discharged through the overflow tube 14. After a relatively large amount of cooling liquid has been discharged from the system, a mixture of liquid and vapor will appear in the glass member 27, which mixture will churn violently as it passes into the tube 40. Of course, it is readily understood that if the condition which creates the relatively 70 high temperature in the cooling liquid is corrected, the cooling liquid will not waste through the glass member 27 and it will again become clear.

The above described signals given in the glass member 27 resemble the signals given in the corresponding member of the device shown and described in my copending application, Serial No. 111,345, filed May 24, 1925, but the duration of the fluctuating column of liquid in the glass dome is somewhat shorter. And when there is insufficient cooling liquid in the system to cause a violently churning mixture of liquid and vapor to pass through the glass member 27, the annular lip 52 will 80 cause the vapor to strike the inner surface of the glass member in such manner that a portion thereof will condense and form a well defined ring of water upon the interior of the glass member. If the cooling liquid continues to waste, the ring will move downward upon the interior surface of the glass member and finally disappear altogether. This ring, of course, indicates to the driver of the automobile that there is a dangerously 90 depleted supply of cooling liquid in the cooling system.

The above described signals given in the glass member 27 indicate four different stages through which the cooling liquid 100 passes when its temperature is raised from atmospheric temperature to a temperature which causes it to continually waste through the overflow tube 14. These stages are as follows:

The first stage: From atmospheric temperature to normal operating temperature. During this stage, no active signal is given in the glass member 27.

The second stage: From normal operating 115 temperature to simmering temperature which precedes violent boiling. An unbroken column of liquid then rises and falls in the glass member 27.

The third stage: From simmering temperature creating comparatively slight pressure to violent boiling which causes a wastage of cooling liquid because of the comparatively high pressure produced in the radiator. The glass member 27 then becomes completely filled with an unbroken column of liquid flowing therethrough and wasting 120 through the overflow tube 14.

The fourth stage: From active boiling and 130 wasting of a still adequate supply of cooling

liquid to a comparatively superheated and wasting of a substantially overheated liquid. During this stage the water ring appears on the interior surface of the glass member 27 and warns the driver that the supply of cooling liquid must be replenished if the engine is to be protected against serious injury.

In Fig. 3, I have shown a fragmentary section through the device which is also shown in Figs. 1 and 2, but in Fig. 3, I have shown the ball 47 so positioned that it does not engage the spherical surface 50 provided upon the tubular member 32. Instead, the ball 47 engages the inner cylindrical surface of the cylindrical portion 48 formed in the tubular member 32. Obviously, the ball 47 and the tubular member 32 cooperate to form a ball and socket connection therebetween and the device functions in substantially the same manner as it does when it is arranged as shown in Fig. 1.

Referring now to Figs. 4 to 6, inclusive, I have shown an indicating device which embodies another form of the invention and is designated generally by the reference characters 60. The improved indicating device 60 is mounted upon the filling tube of an automobile radiator 62, or the equivalent, and preferably comprises an annular member 64 screw-threaded upon the filling tube 61. Any suitable means may be provided for preventing unauthorized removal of the indicating device 60 from the filling tube 61. Thus, I have shown a set screw 66 screw-threaded through the annular member 64 so that it engages the filling tube 61, the set screw 66 being provided with an annular groove 67 underneath its head so that the head may be removed from the shank. Obviously, when this is done, the set screw can not readily be removed from the annular member.

At its upper end, the annular member 64 is preferably provided with a frusto-conical surface 68 upon which a collar 69 is seated, the collar 69 being provided with a frusto-conical surface 70 which conforms to the frusto-conical surface 68. In this instance, an annular groove 72 is provided in the frusto-conical surface 70 to hold a packing ring 73. This construction prevents waste of cooling fluid through the joint between the collar 69 and the annular member 64.

Projecting upwardly from the collar 69 is a glass dome or hollow member 75 which resembles the aforementioned glass dome or hollow member 27. Projecting up into the hollow member 75 is a tubular member 76 which, at its lower end is provided with an outwardly extending annular flange 77 screw-threaded into the collar 69, the arrangement being such that the flange 77 secures the hollow member 75 to the collar 69. As shown, I preferably provide packing 78 between the hollow member 75 and the collar 69 and the flange 77. A plurality of apertures 80

formed in the annular flange 77 permit cooling fluid to flow upward from the radiator 62 into the hollow member 75 from which it is discharged through the tubular member 76.

It will be noted that the upper end of the tubular member 76 is substantially identical in construction with the upper end of the aforementioned tubular member 32, the tubular member 76 being preferably constricted adjacent its upper end to provide a socket 82 in which a ball-shaped end 84 provided upon a tube 85 may be journaled. The tube 85 is mounted upon the upper end of an overflow pipe or tube 89 which projects up into the filling tube 61. The ball-shaped end 84 of the tube 85 is not shown in engagement with the socket 82 but is shown positioned in a substantially cylindrical portion of the tubular member 76. This is in line with the construction shown in Fig. 3 but it is, of course, understood that if it is so desired, the ball-shaped end 84 may be arranged to engage the socket 82.

The upper end of the tubular member 76 is preferably shaped to provide an outwardly extending annular lip 91 which functions substantially in the same manner as the aforementioned lip 52 shown in Fig. 1. The collar 69 in which the hollow member 75 is mounted is pivoted by a pin 94 to the annular member 64 so that the hollow member 75, the tubular member 76 and the collar 69 may be angularly displaced as a unit around the pin 94 to open the upper end of the filling tube 61. This construction permits the supply of cooling fluid in the radiator 62 to be replenished at any time. A lever 97 pivoted by a pin 98 to the collar 69 is engageable with a lug 100 preferably formed integral with the annular member 64. When the lever 97 is in the position wherein it is shown in Fig. 4, it locks the collar 69 against displacement around the pin 95 but it is readily understood that the lever 97 may be swung out of engagement with the lug 100 so that the collar 69, the hollow member 75 and the tubular member 76 may be angularly displaced as a unit in the manner above described.

The operation of the device shown in Figs. 4 to 6, inclusive, is substantially identical to the operation of the device shown in Figs. 1 to 3, inclusive.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. An indicating device of the kind described comprising an apertured closure

- member for the filling opening of an automobile radiator provided with an overflow pipe, a hollow member in which the presence of vapor or liquid may be observed, said hollow member being carried by said closure member and being positioned thereabove to receive vapor and liquid from said radiator through said aperture in said closure member, a tubular member carried by said closure member having an aperture for the passage of fluid from said closure member to said hollow member, and a tube adapted to be positioned upon said overflow pipe and arranged to form a ball and socket joint with said tubular member, said tube being adapted to discharge vapor and liquid from said hollow member into said overflow pipe. 75
2. An indicating device of the kind described comprising an apertured closure member for the filling opening of an automobile radiator provided with an overflow pipe, a substantially transparent hollow member mounted on said closure member and arranged to communicate with the interior of said radiator, a tubular member carried by said closure member and arranged to project up into said hollow member, said tubular member being provided with apertures whereby vapor and liquid may pass from said radiator up into said hollow member, and a tube extending from said tubular member to said overflow pipe. 80
3. An indicating device of the kind described comprising an apertured closure member for the filling opening of an automobile radiator provided with an overflow pipe, a substantially transparent hollow member mounted on said closure member and arranged to communicate with the interior of said radiator, a tubular member carried by said closure member and arranged to project up into said hollow member, said tubular member being provided with apertures whereby vapor and liquid may pass up into said hollow member from said radiator and said tubular member being provided with an outwardly extending annular lip adapted to direct the vapor and liquid against the inner surfaces of said hollow member, and means operatively connecting the tubular member to said overflow pipe whereby vapor and liquid may be discharged from said hollow member into said overflow pipe. 85
4. An indicating device of the kind described comprising an apertured closure member for the filling opening of an automobile radiator provided with an overflow pipe, a substantially transparent hollow member mounted on said closure member and arranged to communicate with the interior of said radiator, a tubular member carried by said closure member and arranged to communicate with said hollow member, said tubular member being provided with apertures whereby vapor and liquid may pass up
5. An indicating device of the kind described comprising an apertured closure member for the filling opening of an automobile radiator provided with an overflow pipe, a substantially transparent hollow member mounted on said closure member, a tubular member carried by said closure member, said tubular member being arranged to communicate with said hollow member and being provided with apertures whereby vapor and liquid may flow from said radiator into said hollow member, and a tube forming a ball and socket joint with said tubular member for operatively connecting it with said overflow pipe so that the vapor and liquid may be discharged from said hollow member into said overflow pipe. 90
6. An indicating device of the kind described comprising an apertured one-piece closure member adapted to be screw-threaded upon the filling pipe of an automobile radiator which is provided with an overflow pipe, a hollow member secured directly to said closure member and positioned thereabove to receive vapor and liquid from said radiator, said hollow member being so constructed that an observer will note the presence of vapor or liquid therein, a tubular member carried by said closure member and communicating with the interior of said hollow member, and means carried by said overflow pipe and arranged to form a ball and socket joint with said tubular member whereby vapor and liquid may be discharged from said hollow member into said overflow pipe. 95
7. An indicating device of the kind described adapted to be mounted at the filling opening of an automobile radiator having an overflow pipe, said device comprising an annular member secured to said radiator at said filling opening, a collar pivoted to said annular member, a substantially transparent hollow member secured to said collar and arranged to communicate with the interior of said radiator through said filling opening, and a tubular member arranged to project into said hollow member, said tubular member having an aperture for the discharge of fluid into said overflow pipe and having an aperture for the passage of fluid from said hollow member. 100
8. An indicating device of the kind described comprising an apertured closure member for the filling opening of an automobile radiator provided with an overflow

pipe, a substantially transparent hollow member mounted on said closure member and arranged to communicate with the interior of said radiator, a tubular member carried by 5 said closure member and having a passage therethrough arranged to communicate with the interior of said hollow member, said tubular member being provided with apertures through its wall whereby vapor and liquid 10 may pass from said radiator up into said hollow member, and means forming a passage whereby said first-mentioned passage communicates with said overflow pipe to discharge vapor and liquid from said hollow 15 member into said overflow pipe.

9. An indicating device of the kind de-

scribed adapted to be mounted at the filling opening of an automobile radiator having an overflow pipe, said device comprising an annular member secured to said radiator at the 20 filling opening thereof, a collar pivoted to said annular member, a substantially transparent hollow member secured to said collar and arranged to communicate with the interior of said radiator through said filling 25 opening, and a tubular member arranged to project into said hollow member, said tubular member being apertured to discharge fluid into said overflow pipe.

In testimony whereof, I have hereunto 30 signed my name.

JOHN W. ANDERSON.
